United States Patent Office.

JACOB K. ANDREWS, EAST LAMPETER TOWNSHIP, PENNSYLVANIA.

Letters Patent No. 99,278, dated February 1, 1870.

IMPROVEMENT IN THE MODE OF ATTACHING HORSES TO VEHICLES.

The Schedule referred to in these Letters Patent and making part of the same.

To all whom it may concern:

Be it known that I, JACOB K. ANDREWS, of East Lampeter township, in the county of Lancaster, and State of Pennsylvania, have invented a new and useful Improvement in the Manner of Attaching Horses to Vehicles; and I do hereby declare that the following is a full and exact description of the same, reference being had to the accompanying drawings, and to the letters of reference marked thereon.

This invention consists in the combination of lever-hooks upon the shaft or pole, with connecting-rods and single-trees, as will be fully described hereinafter.

In the drawings—

Figure 1 represents a side elevation of a pair of shafts with my improvements attached;

Figure 2 represents a plan view of the same;

Figure 3, a plan view of a pole with my improvements attached; and

Figure 4, a view of a pair of hames, so arranged as to be easily detached from the collar, when desired.

To enable others skilled in the art to make and use my invention, I will now proceed to fully describe its construction and operation.

A A represent a pair of ordinary shafts, which are provided, near their front ends, with the lever-hooks a a.

b b represent rods or shafts, extending from the lower arms of the lever-hooks to the ends of the single-tree, as shown.

The hooks proper are caught into the eyes of the hames.

If desired, the single-tree may be located in front of the horse, a cross-bar C being provided for that purpose, which latter may be secured to the shaft in any suitable manner, so as to permit its ready removal, when desired. Spring-catches or simple pins may be used for this purpose.

The single-tree, in front, is connected to the lever-hooks a a by the rods c c.

The location of the single-tree above or below the bar is, of course, immaterial.

A simple modification of this method adapted for two horses is shown in fig. 3. The single-trees in this case also may be in front or rear, as is desired.

By the arrangement herein described, most of the harness ordinarily employed becomes unnecessary; a bridle, collar, and pair of hames, with a choke-strap and simple back-band, is all that is necessary. The devices employed may be easily constructed and applied by any one. The ordinary collar may be employed, but it is better to use one that is broad upon the top, as the load, in this method of hitching, necessarily comes perpendicularly upon the back of the neck; a simple and cheap method of hitching is obtained, as herein described, which is much more comfortable to the animal, also, than the harness ordinarily employed. I do not limit myself to any specific form or special material.

In order to provide for unloosing the horse from the vehicle, when desired, I employ hames of peculiar construction, as shown in fig. 4. These are preferably secured by a lever, which may be operated to unloose them, by means of a string from the vehicle. I do not limit myself to any particular form of hames.

Having thus fully described my invention,

What I claim as new, and desire to secure by Letters Patent, is—

The combination of the lever-hooks and connecting-rods with the single-tree, either before or behind the horse, when applied to a pole or pair of shafts, substantially as described, for the purpose set forth.

This specification signed and witnessed, this 27th day of November, 1869.

JACOB K. ANDREWS.
